HAND GRENADE HOLDER

Grant F. Walton, Medford Lakes, N. J., assignor
of five per cent to William Anderson, New
Brunswick, N. J.

Application June 13, 1951, Serial No. 231,303

5 Claims. (Cl. 224—26)

1

This invention relates to hand grenade holders and more specifically to such a holder as will keep the grenade secured to the person carrying it, permit its quick withdrawal and prevent withdrawal of the safety pin while the grenade is seated in the holder.

All present types of U. S. hand grenades have the same size and type handle and safety pin arrangement. The handle is often used to carry the grenade, by sliding it over a belt or over the top of one's pants. This, however, leaves the grenade none too securely attached to the person and furthermore leaves the safety pin ring hanging free and subject to being accidentally caught on some passing object such as would be encountered in traveling through heavy brush. Such accidental pulling out of the safety pin is rendered virtually impossible if a holder, such as disclosed by the present invention, is used.

The handle is also for the purpose of arming the grenade when it is being used; the handle is spring loaded away from the grenade but restrained by a safety pin. When it is desired to fire the grenade, it is held by gripping the body of the grenade, with the handle under the palm of the hand. Then the safety pin is pulled out by means of the ring attached, and the grenade is armed. Now as soon as the grenade is thrown, the spring throws the handle up and fires the fuse cap, which starts the time delay fuse, which in turn will detonate the main charge after a predetermined time delay. Once the spring has been released by the handle and the cap fired, the fuse will be lit and there is no stopping the explosion of the grenade. It is for this reason that great care must be taken to avoid accidental pulling out of the safety pin.

An object of this invention is to provide a holder for hand grenades to give a secure, safe holder which at the same time allows easy access to the grenade for use.

Another object of this invention is to provide a holder which may be fastened to any appropriate article of wearing apparel. It may be designed for use on a cartridge belt or pack suspenders or on a BAR belt. By making simple changes in the design, it may be made to fit on a piston belt or any other appropriate place on wearing apparel.

A further object of this invention is to provide a holder which will protect and hold in place the safety pin of the hand grenade. Often when traveling through heavy brush, there is considerable danger that the safety pin will be pulled out and for this reason the protection gained by

having a guard for the safety pin of the grenade is particularly advantageous. This holder will prevent the safety pin being accidentally pulled out from whatever cause.

5 The holder of the present invention is a simple, effective means of carrying hand grenades with entire safety. It may be manufactured from a single stamping out of sheet metal of desired thickness. Hence it is very inexpensive to manufacture, especially in large quantities. However, the holder, especially the loop portion thereof, may be made from spring metal which will improve its gripping quality on the belt or clothing of the wearer, but will add to the expense of manufacture.

10 Another object of this invention is to provide a hand grenade holder which is designed to fit on a cartridge belt between pockets of the same, which does not interfere with removal of the cartridges nor with the removal of the grenade itself.

In the drawings:

15 Fig. 1 is a front elevation showing a holder in position on a cartridge belt with a hand grenade in the holder;

20 Fig. 2 shows a side elevation of the holder and hand grenade with the cartridge belt, taken on the line 2—2 of Fig. 1;

25 Fig. 3 is a top or plan view of the holder again in position on a cartridge belt with a hand grenade in the holder;

30 Fig. 4 is a perspective view of the holder itself; and

35 Fig. 5 is a fragmentary perspective view of the bottom of the holder showing the tooth-shaped split portion of the holder.

40 A specific embodiment of the invention is shown in the various figures of the drawings. There is a loop generally indicated by reference numeral 11 which fits over a cartridge belt shown in the drawings by reference numeral 12. This loop is split or open at the bottom as indicated at reference numeral 13 and in this instance the split is formed with tooth-shaped edges as best seen in Fig. 5. The purpose of having these teeth is to provide a gripping action of the loop especially in case the holder is to be used on clothing other than a cartridge belt.

45 A hand grenade as shown in the drawings by reference numeral 14 may be placed in the holder by sliding its handle 15 into the brackets 16. These brackets are so designed that the handle fits easily within the brackets and yet seats firmly when the hand grenade is in its final position because of the widening of the handle 15 at its

upper portion indicated by reference numerals 17 in Figs. 1 and 3. When the hand grenade is in position in the holder, safety pin 18 becomes firmly seated between the sides of guard device 19. This guard device is generally U-shaped in form as may be clearly seen in Fig. 4 and it has wing-like flanges 20 at the ends of the U. These flanges aid in the final seating of the hand grenade 14 in position in the holder and are effective because of the curved shape of handle 15 which allows safety pin 18 to move out away from the body of the holder as it is being lifted out of the holder. The U-shaped guard device 19, abutting against both ends of safety pin 18, when the grenade is seated in the holder, aids in keeping the grenade in the position shown in Figs. 1, 2 and 3. Guard 19 also relieves handle 15 of most of the strain when the grenade bumps against objects when being carried.

Loop 11 of the holder is made up of a body member 21 to which brackets 16 are integrally attached. The back portion 22 of the loop is preferably formed from the same piece of material as the body member 21 and brackets 16. The U-shaped guard member 19 is illustrated as being a separate piece of material from the rest of the loop 11. However, it is obvious that this guard device may be formed out of the same piece of material in the same manner as brackets 16 were formed in this instance. The U-shaped guard member 19 is preferably made of spring steel or other resilient material in order to provide firm and positive seating of the safety pin between its sides.

It is obvious also that the brackets 16 need not be entirely closed across the front. However, it is preferred that they be made entirely closed for greater strength and to present a smoother surface. It will be noted that the ring 23 of the hand grenade may be maintained in a variety of positions. However, the illustrated position is ordinarily the most natural and would be preferred in most instances. It will be noted that the bottom of loop 11 is closed, i. e. its ends are bent under to meet each other. The purpose of this is to provide a surface below the cartridge belt in order that the holder will not slide up on the belt as a hand grenade is removed. It will be noted also that the holder fits snugly between pockets 24 on cartridge belt 12 leaving free access to these pockets and also not impeding the withdrawal of the grenade itself.

A specific embodiment of this invention has been illustrated but is not to be taken as limiting the invention in any way. Reference is made to the appended claims for the scope of this invention.

I claim:

1. In a holder for a United States style hand grenade having a handle thereon and a safety pin located transversely to said handle, said holder having a rigid body member with loop means attached thereto for fastening the holder to an article of wearing apparel, and bracket means open at both ends for receiving the handle of said grenade therethrough, a guard device attached to said body member to protect against accidental removal of the safety pin comprising a U-shaped member having flat resilient material sides, each of said sides having a flaring end to guide the safety pin into a secure position between said sides.

2. The combination according to claim 1 wherein the end of each of the sides is rounded.

3. The combination according to claim 1 wherein the sides of said U-shaped member are sloped nearer together at the top than at the bottom thereof.

4. A holder for a United States type hand grenade having a handle and a safety pin transverse thereto comprising a longitudinally elongated body member, transversely located bracket means attached to said body member for receiving the handle of a grenade therethrough, laterally extending guard means attached to said body member above said bracket means comprising flat resilient material side elements for gripping the safety pin therebetween when a grenade is in place in the holder, and means for fastening said body member to an article of wearing apparel.

5. The combination according to claim 4, wherein said side elements are sloped somewhat nearer together at the tops than at the bottoms thereof, and further including rounded flanges at the ends of said side elements, said flanges flaring in a divergent manner to guide the safety pin into secure engagement between said side elements.

GRANT F. WALTON.
